UNITED STATES PATENT OFFICE.

WILLIAM W. BEWSIC, OF RED BANK, NEW JERSEY.

UNDERGARMENT.

971,659.

Specification of Letters Patent.

Patented Oct. 4, 1910.

Application filed February 1, 1909. Serial No. 475,394.

To all whom it may concern:

Be it known that I, WILLIAM W. BEWSIC, citizen of the United States, residing at Red Bank, in the county of Monmouth and State of New Jersey, have invented certain new and useful Improvements in Undergarments, of which the following is a specification.

This invention relates generally to apparel for children and particularly to waterproof undergarments as a covering for the hips and thighs.

More specifically the invention relates to a child's garment which may be opened out in flat form so as to be applied in the manner of applying diapers and comprising a body portion having lateral members arranged to be brought around the hips and fastened together in the front and also a centrally located flap arranged to be drawn between the legs and up into the crotch together with angular strips having cords at their free ends and arranged to be wound tightly about the edges of the garment surrounding the limbs of the child and to be secured in such drawn position whereby moisture is prevented from passing around the limbs and saturating other articles of apparel. This arrangement forms suitable openings for the legs of the wearer.

Invention also resides in the arrangement of the garment so that the crotch portion when drawn between the limbs of the wearer may be readily secured by a single fastening means to both of the side portions.

The invention may be further briefly summarized as consisting in the construction and combination of parts hereinafter set forth in the drawings, specification and claims.

Referring to the drawings Figure 1 represents the device opened and spread out to clearly set forth the construction and arrangement thereof; Fig. 2 shows a front view of the device applied; Fig. 3 is an elevation with one lateral member unfastened and spread out to more clearly show the construction and Fig. 4 is a rear view applied showing the manner in which the strips pass around the limbs of the wearer.

The invention may be carried out in any preferred manner and any suitable pattern or design of garment may be provided with my invention so long as it possesses the necessary features but I have shown one form in the drawings which meets the re-

quirements very effectively and in such embodiment 1 represents a body portion having a centrally located flap 2 adapted to be drawn tightly between the legs of the wearer 60 and a waist band 3 provided in the back with openings 4 for receiving a tape 5 to be drawn and tied in the adjustment of the waist band to the wearer.

At one end the waist band 3 has a button 65 6 coöperating with a button hole 7 to form a fastening device for the band at the waist and further has secured under it a loop 8 the purpose of which will be later described. The lateral members 9 and 10 of the garment are drawn around in front and are provided with button holes at 11 and 12 which both fasten over a button 13 carried by the flap 2 when it is drawn up in front after being passed between the limbs of the 75 wearer. The side portions 9 and 10 are extended in long angular strips 14 and 15 adapted to be wound around the corresponding leg to the back and thence around the back and to the front on the outside 80 and held by tapes 16 and 17 fastened to the loop 8 as clearly shown in Figs. 2 and 4.

From the foregoing construction it will be seen that the strips 14 and 15 may be drawn around the limbs of the child and 85 over the edges of the body portion of the garment at the leg openings so that moisture may not pass out at these points.

Having described my invention, I claim—

1. As an article of manufacture, a child's 90 undergarment having openings for the thighs, an extension secured to the garment adjacent to each thigh opening and adapted to be wound snugly about the edge of the garment at the corresponding thigh openings, tapes secured to the free ends of said extensions and means secured to the waist band and to which said tapes may be secured.

2. As an article of manufacture, a child's 100 undergarment comprising a body portion, a crotch portion, lateral portions adapted to be brought around in front, means for holding the same together, an extension upon each lateral portion and arranged to pass 105 between the thighs and to be wound snugly about the edge of the garment at the corresponding thigh opening and tapes upon the ends of said extensions and secured to the waist band for holding the same in 110 place.

3. As an article of manufacture, a child's

undergarment comprising a waist band, a body portion, a crotch portion, lateral portions arranged to pass around the hips and fastened in front, means for securing the 5 ends of the crotch portion to said lateral portion when they are fastened, an extension on each lateral portion and arranged to extend between the thighs and to be wrapped snugly around the edge of the garment about the thighs, tapes secured to the 10

free ends of said extensions and a loop carried by the waist band in front to which said tapes may be secured.

In testimony whereof I affix my signature in presence of two witnesses.

WM. BEWSIC.
